L. B. FISHER.

Seed-Planter.

Patented Mar. 7, 1854.

No. 10,607.

UNITED STATES PATENT OFFICE.

LUTHER B. FISHER, OF COLDWATER, MICHIGAN.

IMPROVEMENT IN SEED-PLANTERS.

Specification forming part of Letters Patent No. 10,607, dated March 7, 1854.

To all whom it may concern:

Be it known that I, L. B. FISHER, of Coldwater, in the county of Branch and State of Michigan, have invented a new and useful Improvement in Corn-Planters; and I do hereby declare that the following is a full, clear, and exact description of the construction and operation of the same, reference being had to the annexed drawings, forming part of this specification, in which—

Figure 1 is a side elevation of the planter. Fig. 2 is a front elevation of the same. Fig. 3 is a section on line $x x$ of Fig. 1, through the axis of the driving-wheels.

Similar characters of reference in the several figures denote the same part of the apparatus.

The object of my invention is to enable the operator so to deposit the several hills as to form right lines across the field, as well as in the direction of planting. This has frequently been attempted; but in most cases the slipping of the wheels and various other causes have rendered the deposition of the grain so irregular in position with respect to the planted portion that the hills are aligned in one direction only, making it impossible for the farmer to cross-plow the field in the process of cultivation. I design to furnish an adjustment which shall correct the irregularity of deposit during the planting process and render the hills at the completion of the operation as correctly aligned in the cross-direction as they are in the direction of planting. The invention consists in making the rim of the wheel which operates the planting arrangement with an opening in its perimeter, and securing the same by rods to lugs of a divided hub, which semi-hubs are movable longitudinally upon the driving-shaft by a combination of levers and screws, hereinafter to be described, so that the separation of the semi-hubs shall diminish the circumference of the wheel and their union increase it.

In the drawings, A is the frame; B, the handles; C, the driving-shaft, and D and E the wheels. The wheel D turns loosely upon the shaft C, and does not affect the planting apparatus, while the portion $a b$ of the shaft C, upon which the hub of the wheel E fits, is of a square cross-section, so that the revolution

of the said shaft is governed by the rotation of the wheel E. The wheel E consists of a cut rim, c , having between its extremities an opening, $e e'$, Figs. 1 and 2. On the interior surface of this rim are the lugs d , attached to which and the lugs f on the semi-hubs $H H'$ are the inclined rods R , running alternately in opposite directions, except at the extremities of the rim c , where there are two rods running to lugs opposite to each other on the semi-hubs $H H'$. This arrangement forms a strong, substantial wheel for rotating the shaft C and governing the planting. The semi-hubs $H H'$ have each a groove, g , in which rest the forks h of levers $I I'$, which have their fulcra at $i i'$ on the horizontal bar O, and their upper extremities inclosing the screw S, as shown in Fig. 1, each of the rear branches of the upper forks, l , having a small projection, m , which enters the thread of the screw S, and as the screw is turned gives the levers $I I'$ a motion about their fulcra and causes the semi-hubs $H H'$ to traverse the shaft C. The edges of the levers $I I'$ are slotted to admit the scraper P, the arms n of which pass through the levers and are held between the pins p and q , so as to be governed by the movement of the levers. The object of this scraper is to remove all earth adhering to the rim, which would, by continual packing, increase the diameter of the wheel and derange the planting apparatus.

Any of the usual methods of depositing the grain may be used, the rotation of the shaft C affording the means of governing the intervals of dropping through well-known devices, the invention herein described having for its object the accelerating or retarding of said rotation, as the case may require.

The operation of my improvement is as follows: The diameter of the wheel E being regulated, as above described, to the required interval of dropping, the planter is driven the length of the field, depositing the requisite number of hills of grain, and at each revolution of the wheel E leaving a mark made by the opening $e e'$. On the return the planter is started so that the first hills deposited shall be in line with the last hills of the previous course, and as the implement advances the operator will observe the position of the marks

made by the opening $e e'$ with respect to those made during the advance, and when found to deviate materially from alignment he will turn slightly the screw S , so as to separate the semi-hubs and diminish the diameter of the wheel when the new marks are in advance of the old, and perform in the reverse manner when they are in rear. In this manner any slight distance gained or lost, which in traversing the length of the field would become considerable, is here promptly counteracted during the progress of the planter, and each hill made so as to differ in no important degree from the line of those opposite it in the finished rows.

The scraper P is arranged so that its edge shall always pass near the outer surface of the rim c , the pressure of the pins q on the under edges of the arms n raising the scraper as the levers bring the semi-hubs together and expand the wheel, and the pins p depressing the scraper as the wheel contracts, thus rendering it self-acting and always in position to relieve the rim from any accumulation of earth. This wheel may be employed in single planters with the same facility as in the one described, slight

and unimportant modifications in the manner of connecting it with the implement being the only points in which it will differ with the double planter above set forth.

What I claim as my invention, and desire to secure by Letters Patent, is—

1. Constructing the driving-wheels of planters with cut rims and divided hubs, substantially as described, said hubs being made to traverse the driving-shaft by means of forked levers $I I'$, operated by a screw, S , or its equivalent, for regulating the alignment of the hills in a cross-direction, as herein fully set forth.

2. The scraper P , in combination with the pins p and q , and levers I and I' , arranged and operating substantially as described, for preserving a given space between the edge of the scraper and outer surface of the rim of the wheel, as herein specified.

In testimony whereof I have hereunto signed my name before two subscribing witnesses.

LUTHER B. FISHER.
